DESIGN FOR A PIANO ACCORDION

Harry Buegeleisen, New York, N. Y.

Application November 14, 1936, Serial No. 65,911

Term of patent 7 years

To all whom it may concern:

Be it known that I, Harry Buegeleisen, a citizen of the United States, residing at New York, in the county of New York and State of New York, have invented a new, original, and ornamental Design for Piano Accordions, of which the following is a specification, reference being had to the accompanying drawings, forming part thereof.

Fig. 1 is a front perspective view of the piano accordion, showing my design; and
Fig. 2 is a rear elevational view thereof.

I claim:

The ornamental design for a piano accordion as shown.

HARRY BUEGELEISEN.
